PETER GRABLER, OF ROCKY RIVER, OHIO, ASSIGNR OF ONE-HALF TO CHARLES E. DAY, OF LAKEWOOD, OHIO.

COPYHOLDING APPARATUS.

Application filed January 16, 1925. Serial No. 2,720.

My invention relates to apparatus adapted to hold sheets or books while copies are being made thereof.

One of the objects of my invention is a simple, inexpensive, and easily operable copy holding apparatus.

Another object is a convenient and easily operable means for holding a copy so that the page to be copied is firmly held in full view of the operator and so that the pages previously copied or not to be copied are firmly held obscured from view of the operator.

Another object is a convenient and easily operable means for indicating the lines to be copied.

Another object is a convenient and easily operable means for indexing the plate which carries the copy.

Another object is a convenient and easily operable means for returning the plate to original position from any indexed position and to any desired position.

Another object is to eliminate noise when the apparatus is operated.

Another object is to balance the plate so that the operator does not need to overcome the weight of the plate and of the copy while indexing the same.

Another object is to arrange this balance so that the same increases progressively as the plate travels downward toward lowest position to prevent the plate from heavily or noisily striking the abutment thereof.

Another object is to adjust the balance of the plate when different weights of copies are supported thereon.

Another object is to be able to fold up the apparatus for the purpose of storage or shipping or when not in use.

I am aware that copy holding apparatus have been made resembling that of the present invention, but the copy holding means of the prior art have many inconveniences and disadvantages. The present invention aims to provide a copy holding apparatus which eliminates the inconveniences and disadvantages found in the prior art.

To enable others to fully understand my invention, I will describe the same as illus-

trated in the accompanying drawings in which:

Fig. 1 is a front view of a copy holding apparatus embodying the features of my invention, the copy support plate is shown as moved up some distance to disclose some of the operating mechanism back of this plate. 55

Fig. 2 is a plan view of Fig. 1, shown narrower to accommodate the size of the sheet, and showing the relations of the plate 60 to the copy clip and to the copy holder in operative positions.

Fig. 3 is an end view of the upper end of Fig. 1, taken at 3, and showing the copy clip and the copy holder in inoperative positions and on a larger scale. 65

Fig. 4 is a section of the upper end of one of the guide bars, on a larger scale, taken on a vertical plane, and showing the non-metallic sleeve on the end of the guide 70 bars and the manner of connecting the upper end of the guide bars to the cross-arm.

Fig. 5 is a section, on a larger scale, taken on a horizontal plane indicated by the line 5—5 in Fig. 1, showing the non-metallic 75 rollers as related to the plate and to the guide bars.

Fig. 6 is a section, taken on a vertical plane indicated by the line 6—6 in Fig. 11, showing the operating shaft on a larger 80 scale.

Fig. 7 is a section, taken on a horizontal plane indicated by the line 7—7 in Fig. 11, on a larger scale, showing the upper sprocket and the cover and the cross-arm in relation 85 to the plate and to the guide bars.

Fig. 8 is a section, taken on a vertical plane indicated by the line 8—8 in Fig. 11, on a larger scale, showing the adjustable joint or journal of the line indicator mechanism. 90

Fig. 9 is a vertical section taken on a plane indicated by the line 9—9 in Fig. 6, showing the adjustable journal between the horizontal arm and the base. 95

Fig. 10 is a section, taken on a vertical plane indicated by the line 10—10 in Fig. 6, showing the brake and the shaft operating mechanism.

Fig. 11 is a section, taken on a vertical 100

plane indicated by the line 11—11 in Fig. 1, showing the sprocket and chain arrangement and the operating mechanisms more clearly.

5 Similar reference characters refer to similar parts throughout the views.

The apparatus shown in the accompanying drawings comprises, principally, the base A, the copy support plate B, the line 10 indicator mechanism C, and the arm D.

The base A comprises the foot 10 and the upwardly extending cover 11 having the bottom thereof secured to the foot 10 by screws or other means. The cross-arm 12 is secured 15 to the upper end of the cover 11, by spot welding, or screws, or by clinching materials, or in any other suitable manner and extends to each side of the cover 11.

The guide bars 13 and 14, round in the 20 present instance, extend upward from the foot 10 and have the lower ends thereof secured to the foot 10 and the upper ends thereof secured to the respective ends of the cross-arm 12.

25 The plate B has the sides 15 thereof curved to partly encompass the bars 13 and 14 with a clearance therebetween as seen in Figs. 5 and 7 and is adapted to slide up and down or vertically in relation to the guide bars.

30 As best seen in Fig. 5, the rollers 16 are journaled on the pins 17 on the back of the plate B, near the bottom thereof. Each of the rollers 16 has the groove 18 in the outer circumferential surface thereof and is 35 spaced so that this groove engages the respective guide bar and thereby guides the lower end of the plate in its vertical movement.

As best seen in Fig. 4, the upper end of 40 each of the bars 13 and 14 is reduced in diameter, the sleeve 19 extends over this reduced end, and the nut 20 is threaded to this reduced end to retain the sleeve 19 in position. Each end of the cross-arm 12 is provided with the ear 21 extending over this reduced end of the guide bar between one end 45 of the sleeve 19 and the nut 20. The sleeves 19 fit slidably into the curved sides 15 of the plate B and guide the upper end of this plate 50 in its vertical movement.

The rollers 16 and the sleeves 19 are made of non-metallic material, such as fiber or rubber, to prevent metal to metal contact between the plate B and the bars 13 and 14 to 55 silence the operation of the plate B.

The rear bracket of the line indicator mechanism C is composed of the bar 22, round in the present instance, extending across the back of the plate B and the ends 60 23 extending forward of the bar 22. The outer end of each of the ends 23 is provided with the boss 24.

The bracket supporting the line indicator mechanism C is formed of sheet metal and 65 comprises the base 25, the loop 26 encom-

passing a portion of the bar 22, and the flange 27 superimposed over the base 25. The screws 28 pass through the cover 11 and through the base 25 and through the flange 27.

70 The bar 22 can rotate in the loop 26 and this loop can be adjusted, by manipulation of the screws 28 as is well known in the art, to create sufficient friction between the loop 26 and the bar 22 to retain the rear bracket 75 in adjusted position but to permit this rear bracket to be adjusted without manipulating the screws 28. With this arrangement, one pair of screws secures the bracket to the base A and also provides for adjustment of the joint between the loop 26 and the bar 22.

The front bracket of the line indicator mechanism C comprises the bar 29, round in the present instance, and extending across 80 the front of the plate B, and the extends 30 extending backward of the bar 29, and the journal portions 31 substantially parallel with the bar 29.

85 As best seen in Fig. 8, each of the bearings 32 has one end thereof secured to the boss 90 24 and the other end thereof provided with a taper external thread. The journal portions 31 are journaled in the bearings 32 each of which is split longitudinally. The adjusting nut 33 is provided with an internal taper thread adapted to the external thread on the bearings 32. With this arrangement, the portions 31 can rotate in the bearings 32 and these bearings can be adjusted, by manipulation of the nuts 33 as 95 is well known in the art, to retain the front bracket in adjusted position but to permit this front bracket to be adjusted without manipulating the nuts 33.

100 The line bar 34, of the line indicator mechanism C, made of sheet metal in the present instance, has the lower end 35 curved to encompass the bar 29 and extends substantially the full length of the bar 29. In the present instance, the end 35 is originally 105 made smaller than the bar 29 and is provided with inherent spring tendency so that this end 35 clamps lightly onto the bar 29 and thereby creates sufficient friction between the end 35 and the bar 29 to permit the bar 34 110 to be adjusted on the bar 29 and to retain this adjusted position.

115 It is observed that the line indicator mechanism C has the rear bracket adjustable on the plate B, and the front bracket adjustable on the rear bracket, and the line bar adjustable on the front bracket. This arrangement permits of a wide range of adjustment and the adjustment features of the joints in this indicator mechanism C permits of easy manual adjustment of the line bar and of taking up wear and thereby increases the efficiency of the apparatus and prolongs the life of this mechanism.

120 The upper end of the plate B is provided 120

with the horizontal flange 36 and the vertical flanges 37 projecting beyond the sides 15. A bracket 38 is secured to each of the flanges 37 and each bracket 38 extends above 5 the flange 36.

The copy holder comprises the bar 39, the crank portion 40 on each end of the bar, the journal portion 41 adjacent each of these crank portions and journaled in the bracket 10 38, and the handle portion 42 provided with the knob 43. The friction rollers 44 are journaled on the bar 39 to facilitate the removal of copy sheets from the plate by permitting these rollers to rotate so that the 15 copy holder need not be operated manually when a sheet of copy is removed from the front of the plate B.

This copy holder is forced toward the plate B and is also held in inoperative position by the springs 45 one end of which is secured to the crank portion 40 while the other end is secured to the bracket 38. It is observed that the springs 45 are so disposed that they force the bar 39 upward after the 20 same is moved upward manually to or just beyond the neutral plane of both ends of the springs. This forced upward movement of the bar 39 continues until the crank portions 40 abut the flanges 46 on the brackets 38 whereby further upward movement of the 25 bar 39 is arrested as seen best in Fig. 3. The springs 45 retain the bar 39 in this inoperative position until the bar 39 is moved downward manually to or just beyond the neutral 30 plane of both ends of the springs whereupon these springs force the bar 39 toward the plate B and clamp the copy 47 thereon as best seen in Fig. 11.

The copy clip comprises the bar 48, the 40 crank portion 49 on each end of this bar and looped to form a handle, and the journal portion 50 adjacent each of the crank portions and journaled in the bracket 38 on a plane a little lower than the journals on 45 the copy holder.

This copy clip is forced down upon the edge of the flange 36 and is also held in inoperative position by the springs 51 one end of which is secured to the crank portion 49 while the other end is secured to the bracket 38. The springs 51 act and are disposed in a manner similar to the springs 45. Since the copy clip is journaled in the bracket 38 in a lower plane than the copy holder, the crank portions 49 abut the crank portions 40 when the bar 48 is in inoperative 55 position.

The copy clip is manually moved to or past neutral position and either into inoperative or into operative position similar to the copy holder. When in operative position, the bar 48 clamps the discarded sheets, 60 52 for instance, on the back of the plate B as best seen in Fig. 11.

65 It is to be observed that the arrangement

of the copy holder and the copy clip effectively holds the copy to the front of the plate and the discarded sheets to the back of the plate when these mechanisms are in operative or holding positions and also retains the copy holder and the copy clip in inoperative or releasing positions above the plate and thereby leaves both hands of the operator free to manipulate the copy and provides more clear space on and around the plate for such manipulation of the copy.

The foot 10 is provided with the upwardly extending lugs 53 and 54. The shaft 55 has the reduced end 56 and is journaled in the lug 54 near this reduced end. The other 70 end of the shaft is hollow and open and extends not quite to the lug 53.

The plug 57 is unrotatably mounted in the lug 53 and has the bearing portion 58 fitting into the open end of the shaft 55 and the polygonal portion 59, four sided in the present instance, projecting further into the hollow shaft 55.

As best seen in Fig. 6, the spring 60 is inside of the hollow shaft 55 and one end of this spring is secured to the shaft through the hole 61 therein. The other end of the spring 60 is secured to the plug 62 which has a polygonal opening through which the portion 59 passes. Since the portion 59 is 90 unrotatably mounted and since the plug 62 is unrotatable in relation to the portion 59 and since the spring 60 has one end secured to the shaft 55 which can rotate and the other end secured to the plug 62 which can not rotate, a rotation of the shaft 55 will wind up the spring 60.

The sprocket 63 is secured to the shaft 55 and rotates therewith. The sprocket 64 is journaled on the cross-arm 12 by means of 105 the pin 65 supported in oblong openings to permit of adjustment of the chain 66 which connects the sprockets 63 and 64.

The lug 67 is secured to the back of the plate B and projects backward sufficiently 110 far to engage the links of one side of the chain 66 is best seen in Fig. 11.

The arm D forms part of the base A, extends forward of the foot 10, and has one end thereof journaled on the shaft 55 on the 115 outside of the lug 54.

In order to provide adjustment for this journal and to prevent the shaft 55 from moving lengthwise, I split this journal and provide the screw 69 traversing this split 120 and located so that a portion of the body thereof engages the groove 70 in the shaft 55 to prevent longitudinal movement of the shaft. By manipulation of this screw 69, the friction of this journal can be adjusted 125 so that the plate B can be tilted into desired position and remain in this position.

By journaling one end of the arm D on the shaft 55, the arm with the levers thereon can be rotated to a position alongside of one 130

side of the plate B so that the apparatus can be folded up for the purpose of storage or shipment. To permit this apparatus to be laid or moved on a surface, without scratching or otherwise marring that surface, I provide the rubber knob 71 on the cover 11 and the rubber knobs 72 on the foot 10. It is observed that the knobs 72 are secured to the ears 73 of the foot 10, that the sides of the knobs 72 extend beyond the ends of the ears 73, that the apparatus rests in the ends of the knobs 72 when the same is in operative position, and that the apparatus rests on the side of the knobs 72 and on the end of the knob 71 when the apparatus is in inoperative position or folded up.

The cup 74 is screwed onto the shaft 55 adjacent the arm D and the cap 75 is journaled on the reduced end of the shaft 55 and held in longitudinal position thereon by the nut 76.

The stop bracket 77 is secured to the arm D and extends into the cup 74 where it is provided with the bumper 78, of rubber or other cushioning material.

The block 79 is secured to the inside of the cap 75 at an angle as best seen in Fig. 10 and has the notch 80 and the cushioning bumper 81 anchored therein.

The roller 82 lays loosely between the inner circumferential wall of the cup 75 and the bumper 78 and the block 79.

The index lever 83 is fulcrumed on the arm D intermediate its ends. The inner end of the lever 83 is provided with the slot 84 to engage the pin 85 secured to the cap 75. The spring 86 normally holds the inner end of the lever 83 down and the adjusting screw 87 is provided to adjust the up and down movement of this inner end of the lever 83.

The housing 68 is secured to the arm D, has the outer wall 88 substantially tangent to the outer circumferential wall of the cup 74, and also has the top wall 89. The roller 90 normally lays between the wall 88 and the outer circumferential wall of the cup 74 due to its own weight. The top wall 89 prevents the roller 90 from leaving the housing 68 when the same is moved upward.

The release lever 91 is fulcrumed on the arm D intermediate its ends. The inner end of the lever 91 projects through the opening 92 in the housing 68 below the roller 90. The spring 93 normally holds the inner end of the lever 91 in lowest position.

As to operation:—

Due to gravity, the roller 90 normally contacts the wall 88 and the outer circumferential wall of the cup 74 and thereby wedges itself between these walls and acts as a brake to prevent the rotation of the shaft 55 in the direction of the arrow shown in Fig. 10 while in this position although the shaft 55 can rotate freely in the opposite direction. When the outer end of the

lever 91 is pressed down, the inner end moves upward and thereby raises the roller 90 out of contact with the wall 88 and the outer wall of the cup and releases the brake and permits the shaft to rotate in either direction.

As best seen in Fig. 11, one of the links of the chain 66 engages the lugs 67 to operate the plate B. The plate B is balanced by manually disengaging the chain link from the lug 67 and manually moving the chain in the direction shown by the arrow in Fig. 11. This movement of the chain rotates the shaft 55 and winds up the spring 60 and is continued until the strength of the spring is equal to the weight of the plate at which stage the chain link nearest the lug 67 is hooked over this lug.

When different weights of copy are placed on the plate B, the above balancing operation is continued until the strength of the spring is equal to the combined weight of the plate and the copy.

After the apparatus is so balanced, the plate remains in any vertical position because the roller 90 acts as a brake and prevents the shaft 55 from rotating in the direction which would permit the plate to move downward as long as the release lever 91 is in normal position.

When it is desired to move the plate B upward, the outer end of the lever 83 is pressed down causing the inner end thereof to move upward which movement also moves the pin 85 upward and rotates the cap 75 on the shaft 55. When the cap so rotates, the block 79 moves therewith and wedges the roller 82 between the inner circumferential wall of the cup 74 and the block 79, thereby causing the cup 74 and the shaft 55 to rotate as far as the adjusting screw 87 permits.

This rotation of the shaft 55 moves the chain 66 and consequently also moves the plate B through the lug 67.

When the pressure on the outer end of the lever 83 is released, the spring 86 returns the lever 83 to original position, thereby rotating the cap in opposite direction and releasing the block 79 from the roller 82 and permitting the same to drop noiselessly upon the bumper 78 to original position. The block 79 naturally follows the roller 82 in this downward movement and the bumper 81 noiselessly abuts the roller 82 at the end of this movement.

During the upward movement of the plate B, the spring 60 unwinds but a fairly even balance is maintained due to the length of the spring. The spring again is wound up during the downward movement of the plate.

When it is desired to move the plate B downward, the outer end of the release lever 91 is pressed down which movement releases

the brake previously described and permits the shaft to rotate in either direction, thereby permitting the plate to move downward due to gravity since the spring 60 is now 5 partly unwound and the previous balanced condition has been disturbed but is again restored as the plate moves downward.

This downward movement of the plate continues as long as the outer end of the lever 91 is held down or until the plate reaches the lowest position at which stage it abuts noiselessly the rubber stool 94 secured to the cross-arm 12. The downward movement of the plate is further cushioned 15 by the spring 60 winding up as the plate moves down.

When it is desired to arrest the downward movement of the plate B at any stage of its travel, it is only necessary to release the outer end of the lever 91 at that particular stage whereupon the roller 90 automatically drops into brake position and arrests further downward movement of the plate. Any further downward movement of the plate can be 25 started by again pressing down the outer end of the lever 91 and can be terminated as just described. Any upward movement of the plate can be started from any position of the plate by pressing down the outer end 30 of the lever 83.

I am aware that copy holding apparatus has been made with a vertically movable support plate and with means for moving this plate upward and downward; therefore, 35 I do not claim such feature broadly, but—

I do claim:—

1. A copy holding apparatus comprising, a movable copy support plate, means for moving said plate, and, means normally locking said plate against movement in one direction and in any position into which said plate may be moved.

2. A copy holding apparatus comprising, a base, a copy support means on said base, a shaft journaled in said base and in operative connection with said support means, an arm rotatable on said shaft, means for operating said shaft mounted on said arm, and said operating means operable when said arm is in any rotated position.

3. A copy holding apparatus comprising, a base, a copy support means on said base, a shaft journaled in said base and in operative connection with said support means, an arm rotatable on said shaft, means for operating said shaft mounted on said arm to rotate said shaft in one direction, means for locking said shaft against rotation in the opposite direction, means for releasing said locking means to permit the rotation of said shaft in either direction, and said operating means and said locking means and said releasing means operable when said arm is in any rotated position.

4. A copy holder apparatus comprising, a

base, at least one metal guide bar extending upward from said base, a metal copy support plate movable longitudinally on said bar, a portion of said plate encompassing the major portion of said bar to guide the same thereon, and means for preventing metal to metal contact between said plate and said bar.

5. A copy holder apparatus comprising, a base, a pair of guide bars extending upward from said base, a copy support plate movable longitudinally on said bars, the sides of said plate partly encompassing said bars, a non-metallic guide roller bearing on the inside of each of said bars and journaled on said plate near the bottom thereof to guide the lower end of said plate on said bars, and a non-metallic guide plug on the upper end of each of said bars within said encompassing sides and guiding the upper end of said plate.

6. A copy holding apparatus comprising, a base, a pair of metal guide bars extending upward from said base, a cover extending upward from said base intermediate said bars, a cross-arm on said cover, the upper ends of said guide bars secured to said cross-arm, a metal copy support plate movable longitudinally on said guide bars, means for preventing metal to metal contact between said guide bars and said plate, and a resilient bumper on said cross-arm.

7. A copy holding apparatus comprising, a base, a copy support means on said base, a shaft journaled in said base and in operative connection with said support means, an arm rotatable on said shaft, and rest pads distributed on said base and on said arm to securely rest the apparatus when said arm is rotated to various positions.

8. A copy holding apparatus comprising, a base, a copy support means on said base, a shaft journaled in said base, a sprocket rotatable with said shaft, a sprocket journaled on said support means, an endless belt means over both of said sprockets, an arm rotatable on said shaft, and both of said sprockets and said arm and said belt means concentric with the longitudinal axis of said shaft to permit said arm to be rotated to various angular relations to said support means and free from interference with the operations of said sprockets and said belt means.

9. A copy holding apparatus comprising, a base, a copy support means on said base, a copy support plate movable on said support means, a shaft journaled in said base, a sprocket rotatable with said shaft, a sprocket journaled on said support means; an endless belt means over both of said sprockets, connector means on said plate, and said connector means adapted to permit the arbitrary engagement and disengagement therefrom without the use of tools with any portion of said

belt means to adjust the relation between said plate and said belt means.

10. A copy holding apparatus comprising, a base, a copy support means on said base, a copy support plate movable on said support means, a shaft journaled in said base, a sprocket rotatable with said shaft, a sprocket journaled in said support means, an endless belt means over both of said sprockets, an arm rotatable on said shaft, both of said sprockets and said arm and said belt means concentric with the longitudinal axis of said shaft to permit said arm to be rotated to various angular relations to said support means and free from interference with the operations of said sprockets and said belt means, means adapted to permit the arbitrary engagement and disengagement thereof without the use of tools with any portion of said belt means to adjust the relation between said plate and said belt means in any angular relation of said support means and said arm.

11. A copy holding apparatus comprising, a base, a shaft journaled in said base, a copy support plate movable in relation to said base and rotatable concentrically with the longitudinal axis of said shaft, operating means for rotating said shaft, and said operating means concentric with said longitudinal axis to permit the operation thereof when said plate is rotated to any position.

12. A copy holding apparatus comprising, a copy support plate movable longitudinally and pivotally, means for moving said plate longitudinally, and said moving means concentric with the axis of the pivot of said plate.

13. A copy holding apparatus comprising, a copy support plate movable longitudinally and pivotally, means for moving said plate longitudinally in one direction, means for locking said plate against longitudinal movement in the opposite direction, means for releasing said locking means, and said moving means and said locking means and said releasing means concentric with the axis of the pivot of said plate.

14. A copy holding apparatus comprising, a copy support plate movable longitudinally and pivotally, means for moving said plate longitudinally in one direction, spring means to counterbalance said plate and wound up by the longitudinal movement of said plate in the opposite direction, means for locking said plate against longitudinal movement in the mentioned opposite direction, means for releasing said locking means, and said moving means and said spring means and said locking means and said releasing means concentric with the axis of the pivot of said plate.

15. A copy holding apparatus comprising, a copy support plate movable longitu-

dinally and pivotally, means for moving said plate longitudinally in one direction, connector means adapted to connect said plate and said moving means arbitrarily and without the use of tools in any relative position thereof, spring means to counterbalance said plate and wound up by the longitudinal movement of said plate in the opposite direction, means for locking said plate against longitudinal movement in the mentioned opposite direction, means for releasing said locking means, and said moving means and said connector means and said spring means and said locking means and said releasing means concentric with the axis of the pivot of said plate.

16. A copy holding apparatus comprising, a base, a vertically movable copy support plate mounted on said base, an arm having one end thereof journaled on said base to permit the same to be rotated in relation to said base and thereby permit said plate to be tilted in relation to said arm and said arm to be folded up to along the side of said plate, means for moving said plate disposed concentric with the journal of said arm to permit said plate to be tilted and said arm to be folded up without affecting the means for moving the plate.

17. A copy holding apparatus comprising, a base, a vertically movable copy support plate on said base, means for moving said plate, an arm extending forward of said base and having one end thereof journaled on said base to permit the same to be rotated in relation to said base and thereby permit said plate to be tilted in relation to said arm and said arm to be folded up to along the side of said plate, and operating levers for moving and stopping said plate mounted on said arm and movable therewith when said arm is rotated.

18. A copy holding apparatus comprising, a vertically movable copy support plate of metal adapted to move on a metal guide and to move downward due to the gravity thereof, means for cushioning the downward movement of said plate, and means for silencing the upward and the downward movement of said plate.

19. A copy holding apparatus comprising, a copy support plate movable longitudinally and pivotally, and means for cushioning the longitudinal movement of said plate in any pivoted position thereof.

20. A copy holding apparatus comprising, a vertically movable copy support plate adapted to move downward due to the gravity thereof, means for cushioning the downward movement of said plate, means for silencing the downward movement of said plate, means for manually moving said plate upward periodically, means for silencing said manually moving means, means for re-

turning said manually moving means to original position, and means for silencing said returning means.

21. A copy holding apparatus comprising, a vertically movable copy support plate adapted to move downward due to the gravity thereof and moved upward by manual means, means for cushioning the downward

movement of said plate, means for adjusting said cushioning means for copies of different weights on said plate, and means for silencing the operation of said manual means and of the downward movement of said plate. 10

PETER GRABLER.
